[57] CLAIM

The ornamental design for lipstick cases, as shown and described.

DESCRIPTION

FIG. 1 is a top perspective view of a lipstick case showing my new design;

FIG. 2 is an exploded perspective view thereof;

FIG. 3 is a bottom plan view thereof;

FIG. 4 is a rear elevational view thereof;

FIG. 5 is a side elevational view thereof;

FIG. 6 is a front elevational view thereof;

FIG. 7 is a top plan view thereof;

FIG. 8 is a top perspective view of a second modified embodiment;

FIG. 9 is an exploded perspective view thereof;

FIG. 10 is a bottom plan view thereof;

FIG. 11 is a rear elevational view thereof;

FIG. 12 is a side elevational view thereof;

FIG. 13 is a front elevational view thereof;

FIG. 14 is a top plan view thereof;

FIG. 15 is a top perspective view of a third modified embodiment;

FIG. 16 is an exploded perspective view thereof;

FIG. 17 is a bottom plan view thereof;

FIG. 18 is a rear elevational view thereof;

FIG. 19 is a side elevational view thereof;

FIG. 20 is a front elevational view thereof;

FIG. 21 is a top plan view thereof.
